SHAVING IMPLEMENT

Joseph Muros, Cambridge, Mass., assignor to
Gillette Safety Razor Company, Boston, Mass.,
a corporation of Delaware

Application September 18, 1937, Serial No. 164,426

3 Claims. (Cl. 30—43)

This invention relates to dry shaving implements of the general type which employ elongated members provided with co-operating transversely disposed teeth relatively movable for a shearing operation. I have discovered that in using such implements a desirably close shaving effect is obtained when a convex contour is imparted to the skin of the user in the shaving area. This tends to make the individual hairs stand out in divergent relation and facilitates the engagement thereof by the shearing teeth close to the surface from which they spring.

These desirable results are accomplished in accordance with the present invention by imparting an inwardly inclined slope to the skin-engaging faces of shearing teeth arranged in opposed series. The teeth may be continuous in transverse contour or they may be interrupted in the longitudinal axis of the implement, but in either case the outer or marginal zones are higher than the inner or central zone of the teeth with the result that, when the implement is pressed against the face in shaving, a convex contour is imparted to the area engaged and a particularly close shave may be obtained with comfort in a short interval of time.

Another feature of my invention consists in shearing teeth which are given a lateral outward taper so that the effective opening between adjacent teeth increases outwardly as the thickness of the teeth increases. Stated in another way, the divergent side walls of adjacent teeth form cavities increasing outwardly in cross section in which the skin of the user takes a convex contour. This results in shearing teeth of strong construction which give a uniform close shaving effect regardless of outwardly increasing thickness.

These and other features of my invention will be best understood and appreciated from the following description of a preferred embodiment thereof selected for purposes of illustration and shown in the drawing, in which:

Fig. 1 is a plan view of the implement on an enlarged scale showing its shearing face;

Fig. 2 is a corresponding view in side elevation;

Fig. 3 is a fragmentary plan view on a still larger scale showing a portion of one series of shearing teeth;

Fig. 4 is a corresponding fragmentary view in elevation;

Fig. 5 is a view on an intermediate scale in end elevation of a portion of the shaving head as positioned upon the face of the user;

Fig. 6 is a cross-sectional view corresponding to Figs. 1 and 2; and

Fig. 7 is a fragmentary cross-sectional view on a still larger scale.

The illustrated implement comprises a casing 10 of "Bakelite" or other plastic material moulded to serve as a handle and also as a housing for the operating motor. The housing 10 is provided in its end with a socket to receive the metallic shaving head of the implement and one wall of this socket is threaded to receive a clamping screw 11 by which the head is securely held in place.

The head is generally elongated and rectangular in outline and as herein shown comprises a pair of identical side members 12 separated by spacing blocks 13 and held rigidly in assembled relation by transverse screws 14. Each of the side members 12 is provided along its upper edge with a series of uniformly spaced transverse shearing teeth 15 and these are arranged in opposed relation with a narrow slot between their inner edges and overhang to some extent the inner vertical side walls of the members 12 as best shown in Fig. 7. The teeth 15 taper inwardly, having flat downwardly and inwardly inclined skin-engaging faces and thus provide on opposite sides of the implement inwardly converging areas 20 which are effective in imparting a convex contour to the skin of the user when the implement is pressed against it.

Each series of teeth 15 is protected by an end guard projection 17 which is wider than the shearing teeth and extends in full width throughout its length. In addition to the vertical side faces which define the individual teeth 15, each of these teeth has oppositely disposed bevelled faces 16 which converge outwardly so that the space between each pair of teeth increases outwardly in cross section in a progressive manner and has greater and greater capacity for receiving the flesh of the face being shaved. The result is that a series of transverse convexities are formed in 40 the skin adjacent to or in the shearing zone, tending to create a divergent condition in the hairs best adapted for close shaving. Further, through the tapering slots the skin of the user extends more and more deeply as the thickness of the 45 teeth increases. The result is that a uniform close shaving action is brought about throughout the full length of the teeth.

Arranged to reciprocate between the two side members 12 is an elongated cutter 20 having 50 spaced upwardly extending flanges which are transversely slotted to form shearing teeth co-operating with the teeth 15, that is, the upper edges of the teeth 21 co-operate in shearing with the lower edges of the stationary teeth 15. The 55

cutter 20 has in its lower face a recess in which is received the upper rounded end of an operating arm or lever 19 which is oscillated at a high rate of speed by the motor and so imparts rapid reciprocation to the cutter.

Having thus disclosed my invention and shown a preferred embodiment thereof for purposes of illustration but not in any limiting sense, what I claim as new and desire to secure by Letters Patent is:

1. A dry shaving implement having opposed side portions with parallel inner walls and inwardly projecting teeth having their shearing walls disposed in a single plane and substantially at right angles to said parallel walls, and a movable cutter having teeth with shearing walls fitting against the walls of said side portions, the teeth of said side portions having outwardly and upwardly inclined upper faces arranged collectively to impart a convex contour to the skin of the user in the shaving area and having outwardly diverging bevelled surfaces widening the space between the teeth as the teeth themselves become progressively thicker.
2. A dry shaving implement including in its structure spaced side members having inwardly overhanging flanges serrated to present teeth with

shearing edges, the shearing edges on both side members lying in a single plane, and a movable cutter having cooperating shearing teeth, the side members being slotted substantially in registration with the spaces of the shearing teeth of the cutter and the resulting teeth being progressively outwardly thickened and outwardly narrowed to present face-engaging areas extending outwardly and upwardly and of tapering width, thereby collectively imparting a convex contour of the skin of the user in the area engaged by the implement.

3. A dry shaving implement comprising opposed side members with inwardly projecting overhanging teeth presenting shearing edges, the shearing edges on both side members lying in a common plane, and a movable cutter having cooperating shearing teeth, the opposed side members being slotted to present face-engaging areas and shearing teeth constantly increasing in thickness as they extend outwardly, thus imparting a transversely concave contour to the face-engaging end of the implement and the side walls of the slots being divergent so that the cross-sectional area of the slots is constantly enlarged as the thickness of the teeth is increased.
